UNITED STATES PATENT OFFICE.

JACOB F. WITTEMAN, OF LAKEWOOD, NEW JERSEY, AND RUDOLPH W. WITTEMAN, OF BROOKLYN, NEW YORK, ASSIGNEES TO AMARANTH MACHINERY AND SUPPLY WORKS, INC., OF NEW YORK, N. Y., A CORPORATION OF NEW YORK.

APPARATUS FOR IMPREGNATING LIQUIDS WITH GASES.

1,128,264.

Specification of Letters Patent.

Patented Feb. 9, 1915.

Application filed July 13, 1911. Serial No. 638,271.

To all whom it may concern:

Be it known that we, JACOB F. WITTEMAN and RUDOLPH W. WITTEMAN, citizens of the United States, and residents of 5 Lakewood, Ocean county, State of New Jersey, and Brooklyn, county of Kings, State of New York, have invented certain new and useful Improvements in Apparatus for Impregnating Liquids with Gases, of which 10 the following is a specification.

This invention relates to improvements in apparatus for impregnating or saturating liquids with gases such as are used for the aeration, carbonation and similar treatments 15 of liquids, and for treating beverages with a gaseous medium in a continuous automatically controlled operation. As such apparatus are commonly used for charging, saturating or impregnating liquids with carbonic acid gas, we will use the term "carbonator" as designating such apparatus in 20 this specification.

The object of our invention is to provide a new and improved carbonator of very 25 simple construction, composed of few moving parts and with all the movable operating devices visible and readily accessible for cleansing and examining, and which carbonator is highly effective, rapid and reliable in operation.

In the accompanying drawing a vertical sectional view through one embodiment of our improved carbonator is shown, parts being in side elevation.

The carbonator, as shown, is composed 35 of a tubular shell 1, with a dished bottom, the shell being open at the top and closed by suitable cover. To the sides of the apparatus lugs 2 are secured, preferably three 40 in number, and to said lugs, legs or supports 3 are attached, the lower ends of which are held adjustable in sockets 4 terminating in ball heads 5 which are clamped in separable floor sockets 6 so as to permit of readily adjusting 45 the shell so that its central axis will be exactly vertical. The shell is provided with a detachable cover 9 resting upon an elastic gasket 10 which in turn rests in a groove in the upper surface of an angle ring 11 secured to the top of the shell on the outside and the cover is held in place on the shell by a series of bolts 12 hinged to the angle ring 11 and adapted to enter notches 13 in the rim of the cover, each

hinged bolt being provided with a winged 55 nut 14 which when drawn up tight press the cover firmly upon the gasket 10. The cover is provided with a central upwardly extending neck 15 in the upper end of which a rabbet is formed for receiving an elastic 60 gasket 16 upon which the lower edge of a cylindrical sight-glass 17 rests, upon the upper edge of which glass rests a similar gasket 18 in a rabbet formed in the cover 19 for the sight-glass, which cover is held 65 clamped in place by bolts 20, hinged to the neck 15, and entering notches 21 in the edge of the cover 19, winged nuts 22 being screwed on the upper ends of said bolts 20. A neck 23 projects upward from the cover 70 concentric with and within the neck 15, said internal neck 23 projecting some distance above the edge of the external neck 15. The upper part of the internal neck 23 is threaded on the outside and on this part is screwed 75 a cap 24, an elastic gasket 25 being interposed between the underside of the cap 24 and the upper edge of the neck 23 to form an absolutely tight joint. The gas supply tube 26 is made integral with a cap 24 and 80 its upper end projects through a stuffing-box 7 on the cover 19 of the sight-glass 17 and the lower end of said tube 26 projects beneath the cap and centrally into the internal neck 23 in the form of a nozzle 27. 85 The internal neck 23 is provided with a series of openings 28 preferably rectangular. A cylindrical valve 29 open at the top and bottom is ground into the internal neck 23 so as to fit snugly, but capable of being 90 moved up and down and by means of a connecting rod 30 a float 31 is suspended from said valve 29 and is moved up and down as the level of the liquid rises or falls in the shell 1. The drawings show this valve 95 in such position as to completely close the openings 28. This, however, is only an extreme position and is only given for the purpose of showing the highest possible position of the valve. From the underside of the cover 100 a series of liquid spreading plates 32, 33 and 34 are suspended by means of bolts 36 surrounded by distancing ferrules 37, located between the several plates. The upper plate 32 is inclined downward and outward from 105 the center and is centrally open for the passage of the rod 30 from which the float is suspended. The next lower plate 33 is inclined

upward and outward from center and is provided on its rim with an upwardly extending flange 38 which extends some distance above the rim of the uppermost plate 32 and 5 this plate 32 is provided at its center with a comparatively large opening 39 through which the liquid can flow upon the plate 34 which like the uppermost plate 32 is inclined downwardly and outwardly and has a central neck 40 projecting up through the opening 39 and affording passage for the suspension rod 30. All these plates have their 10 upper surface corrugated in some suitable manner so as to impede a too rapid flow of 15 the liquid and to cause the distribution into a thin film.

As the upper plate 32 is inclined downward and outward the liquid flows over its corrugations and flows from the rim of this 20 uppermost plate to the rim part of the second plate 33 which is inclined downward and inward and through the central opening 39 of the latter the liquid flows on the lowest plate 34 which is again inclined 25 downward and outward, its rim being close to the wall of the shell on to and down which the liquid flows. The liquid is thus caused to travel in a thin layer over a large area within the shell 1 before it reaches 30 the level of the liquid in the shell.

The liquid supply pipe 41 communicates with the external central neck 15 of the cover and this inlet pipe is connected by a coupling 42 with the casing 43 of a valve 35 44 and this casing also has a neck 45 for attaching the liquid supply hose and a vent 46. It is also provided with a hollow cross piece 47 and with a sight-glass 48 and with a waste valve 49. At the bottom the shell 40 has an outlet neck 50 connected by a suitable coupling 51 with an outlet pipe 52 having an outlet valve 53 and a waste valve 54. The beer which is drawn out of the shell or receptacle 1 passes out through the 45 valve 53 to the storage vessels when said valve is open. When this valve is closed the waste beer, washing water or other liquid contained in the vessel can be drawn off through the waste stop valve 54 which is 50 then opened but ordinarily remains closed. The upper end of the gas pipe 26 previously described is connected by a coupling 55 to the gas pipe 56, the opposite end of which is connected by a coupling 57 with a neck 55 58 on the cover. The gas supply pipe 59 is connected with the gas pipe 56 and is provided with a suitable cock or shut-off valve 60 by means of which the supply of gas can be regulated or shut off. The cover 60 19 of the sight-glass 17 is provided with a vent 61 and the gas pipe 56 is provided with a vent 62.

In operating the apparatus described for the purpose of carbonating, the valves 44 and 60 are closed and the valves 61 and 62

are opened and through one of the bottom valves 53 or 54 the apparatus is filled to the top with clear water so as to expel all the air contained in the apparatus through the vents 61 and 62. These vents are then 70 closed and through the pipe 56 gas under pressure is admitted by opening the valve 60, from the pipe 59, and this gas enters at a pressure of about one third of that at which impregnation is to take place and 75 this gas forces the water through the waste valve 54 which is closed as soon as all the water has been displaced. The gas is only admitted at one-third of the pressure at the beginning of the operation to prevent over 80 impregnation of the beer and when the operation has been fully started it is then admitted at full pressure. The gas inlet cock 60 is then closed and the liquid to be impregnated is then turned on to inlet 45, 85 the shut-off valve 44 being closed and the vent 46 and waste valve 49 remaining open until all water, which may have remained in the supply conduit, has passed off, or until the agitation of the liquid, visible through 90 the sight-glass 48 in the cross piece 47, indicating the presence of air has ceased, this air being vented off through the vent 46. When solid liquid, that is liquid containing no air, shows through the sight-glass 48, 95 the valves 46 and 49 are closed the valve 44 is opened to permit the liquid to pass to the space between the necks 15 and 23 in the cover and into the chamber 17 and from the same through the ports 28 into the neck 100 23 from which it flows upon the uppermost spreading plate 32, the tubular valve 29 now being in its lowermost position. The liquid spreads over the spreading plates and from the lower one thereof to the inner 105 surface of the wall of the shell running down the latter as a thin film and finally collects in the bottom of the shell and as it rises compresses the gas within the carbonator. The liquid rises until the float 110 lifts the controlling valve 29 to such an extent that it closes the inlet ports 28 or until the pressure created in the apparatus exceeds that of the liquid supply. In the latter case the pressure within the apparatus is reduced by opening the vent 61 so as to re-start the flow of the liquid through the controlling valve until the liquid has reached the level desired in the apparatus and the float is about to throttle the inward 115 flow of the liquid. The vent 61 is then closed, the gas supply cock 60 is opened to such extent as to regulate the gas supply in such a manner as to maintain the desired 120 impregnating gas pressure within the carbonator during the flow of liquid through the same.

The outlet valve 53 having been opened to permit the outflow of the impregnated liquid, the liquid supply controlling valve 130

29 automatically adjusts itself according to the level of the liquid in the carbonator, to throttle, by means of the action upon it by the float, the flow of the liquid in portion 5 to the outflow. The connection between the valve and the float is so adjusted that the upward movement of the valve reduces the effective area of the valve ports whenever the liquid level rises above the 10 normal point at which the liquid supply passing through said valve 29 will equal the outflow through the outlet 53 and vice versa the downward movement of the control valve 29 by the float, will increase the 15 effective area of the inlet ports until the inflow action equals the outflow from the carbonator. Through the automatic regulation of the inflow of liquid by the liquid level within the apparatus while the gas 20 supply is maintained uniform, and the reliable uniform impregnation of the liquid with the gas is secured. The spreading plates, over the corrugated surface of which the liquid is caused to flow constantly break 25 or interrupt or disrupt the thin film of liquid passing over these plates, the area of which is very great compared with the area of the inlet opening, causing the liquid to be exposed to the gas for a controllable 30 length of time as the number and size of these plates may readily be varied to suit the varying conditions and requirements. In addition to the intimate and extended contact between the liquid and the gas in 35 the manner described the increase of absorption of gas is secured by the fact that the beer is agitated in the presence of gas by the suction action resulting from the inflow of liquid through the valve ports 28 40 into the liquid controlling valve and the introduction of a column of gas into this entering, agitated beer through the nozzle 27 extending into the inner neck 23. If for any reason whatever the supply of gas

through the nozzle 27 is decreased and not sufficient, gas can enter to properly impregnate the liquid in the carbonator through the neck 58. The large sight-glass 17 permits of carefully observing the operation of the inlet controlling valve and the sight-glass 62 in the shell permits of observing the operation of the float. Likewise the sight-glass 17 and the sight-glass 48 permit of careful observation of the liquid at the vents 46 and 61. 55

Having described our invention what we claim as new and desire to secure by Letters Patent is—

1. The combination with a carbonating vessel, of an inlet neck, a liquid supply conduit communicating with said neck, a valve for controlling the passage of liquid through said neck, means for automatically operating this valve, a closed transparent chamber surrounding the neck and valve 60 and communicating with the liquid supply conduit, and a gas supply pipe extending through said chamber to the neck, substantially as set forth.

2. The combination with a carbonating vessel, of an inlet neck, a valve controlling the passage of liquid through said neck, a liquid supply conduit leading to said neck and surrounding the same, and a closed transparent chamber surrounding the neck 65 and valve and communicating with the liquid supply conduit, and a venting device on said surrounding chamber, substantially as set forth.

Signed at New York city, in the county 80 of New York and State of New York this 3rd day of July A. D. 1911.
